Primary Examiner — Llorellys Martinez(74) *Attorney, Agent, or Firm* — Birch, Stewart, Kolasch & Birch, LLP(57) **CLAIM**

The ornamental design for a construction furring strip support extension, as shown and described.

DESCRIPTIONFIG. 1 is a front view of a construction furring strip support extension showing my new design;
 FIG. 2 is a back view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof; and,

FIG. 8 is another perspective view of the construction furring strip support extension of FIG. 1, shown in a configuration of use.
 The broken lines in FIG. 8 represent environmental subject matter only and form no part of the claimed design.**1 Claim, 8 Drawing Sheets**(56)
